UNITED STATES PATENT OFFICE

2,474,484

ELECTRIC LIGHTING FIXTURE

Vincent J. Marchese, Brooklyn, N. Y.

Application April 13, 1948, Serial No. 20,771

5 Claims. (Cl. 240—123)

1

This invention relates to electric lighting equipment and more particularly to the electric circuit control of electric lighting fixtures, including portable electric lamps.

An important object of the invention is to provide an electric lighting fixture having a novel electric switch associated with movable and fixed structures of the fixture whereby a slight tilting movement imparted to one structure will cause actuation of the electric switch to either open or close the switch, so that the lamp associated with the fixture will be lighted or extinguished.

Another important object is to provide a novel electric lighting fixture having no electric switch portion, as a button, projecting outwardly from the fixture housing, yet the electric circuit to light the lamp or lamps of the fixture may be actuated from the exterior of the housing.

A further important object is to provide a portable electric lighting fixture, such as a table or floor lamp, which may be carried from place to place without accidentally operating the electric switch associated therewith.

Since the novel fixture preferably includes an outer movable structure which, upon oscillation will open or close an electric circuit, an object of the invention is to provide means, employing parts of the lamp lighting and extinguishing means to cause a visible flasher-type signal in the event the outer movable structure becomes accidentally tilted and remains tilted.

Other objects and advantages of the invention will be apparent during the course of the following detailed description of the invention, taken in connection with the accompanying drawings, forming a part of this specification and in which drawings:

Figure 1 is a vertical section of an electric lighting fixture embodying the invention and including an upper housing portion in a vertical position.

Figure 2 is a vertical section of the lower part of the lighting fixture of Figure 1, with the upper housing portion tilted to actuate an electric switch.

Figure 3 is a longitudinal section of a preferred electric switch which may be employed in the novel fixture.

Figure 4 is a perspective view of a ratchet associated with the switch of Figure 3.

2

Figure 5 is an electric wiring diagram of the fixture.

In the drawings, wherein for the purpose of illustration is shown a preferred embodiment of the invention and wherein similar reference characters designate corresponding parts throughout the several views, the novel electric lighting fixture is designated A and a conventional electric lamp as B.

10 The fixture A is shown as including a reciprocating and tilting housing or housing structure 10, comprising a first or lower housing portion 11 and second or upper housing portion 12, a support structure 13 including a lower support portion 14 over which the lower housing portion 11 extends and an elongated standard 15 carried thereby and supporting an electric lamp base-receiving socket structure 16, with an electric switch assembly 17 carried by the housing 10 and support structure 13. The fixture also includes a solenoid-operated off-and-on switch assembly 18 and electrical wiring 19.

25 The housing structure 10 may be of any suitable material, as metal, hardened plastics, wood or combinations thereof, and the lower housing portion 11 may be bell-like in shape, forming a skirt 20, open at its lower end and the housing portion 11 may terminate at its upper end in a collar 21. From this collar 21 may extend the upper housing portion 12 which is preferably 30 elongated and tubular and fixedly secured to the collar in any approved way, as by rivets 22 which rivets may be employed also to secure a portion of the electric switch assembly 17 to be described.

35 The portion 12 is preferably open at each end. Spaced below the upper open end of the housing portion 12 is a portion of means 23 to loosely support the housing structure 10 by the support structure 13. This may be a flange or shoulder

40 24 fixedly secured to and extending inwardly from the wall of the housing portion 12. Preferably, the flange provides a circular opening 25 and the diameter thereof is greater than the outside diameter of the standard 15 to be subsequently described. This flange 24 may be provided with an upstanding collar 26 engaging the inner surface of this wall and secured to the wall as by screws 27.

45 Referring now to the support structure 13, this 50 may be of metal, plastics, wood and the like or

combinations thereof. The lower support portion or base 14 includes a section 30 preferably somewhat bell-like in shape but smaller than the lower housing portion 11 which extends over it and is spaced therefrom. Thus, the section 30 contains a chamber 31 and from the lower end of the section 30 projects an outwardly-extending, substantially horizontal foot section or flange 32. Closing the mouth of the bell-like section 30 is a cover 33 which may be removably secured to the section 30 as by screws 34. If desired, the lower and vertical faces of the flange 32 may be faced with a protective covering 35, as felt with its outer horizontal face disposed below the horizontal plane of the outer face of the cover 33. The wall of the section 30 may be provided with electric conductor-accommodating passageway or openings 36 and 37, and with an upwardly-opening axially-disposed, screw-threaded opening 38.

The standard 15 is preferably an elongated tube, much smaller in exterior circumference than the interior circumference of the upper housing portion 12 through which it extends, and provided with exterior screw threads at its lower end to accommodate the screw threads of the opening 38. A set screw 39 extending through the wall of the section 30 and to the opening 38 may bear against the standard 15 in order to secure it against accidental rotation with respect to the support portion 14. The upper end of the standard 15 may be exteriorly screw threaded to receive the socket structure 16 to be subsequently described. Spaced below the upper end of the standard 15 and secured thereto, as by a screw 40 is a collar 41 constructed and arranged to support, upon its upper end, the innermost portions of the shoulder or flange 24 so that the shoulder and structure secured thereto may be rocked upon the upper face of the collar 41 which has an outer circumference much less than the inner circumference of the adjacent parts of the upper housing portion 12. This collar 41 forms, with the shoulder or flange 24, the means 23, referred to heretofore.

As stated, the standard 15 receives the socket structure 16 at the upper end of the former and this structure may be of any desirable material, as metal, plastic or wood. In the example shown, the structure 16 includes a body portion 45 having an upwardly-opening, partly screw-threaded electric lamp base-receiving socket 46 and a conductor receiving passageway 47 leading thereto and with the lower portion of the wall of this passageway provided with screw threads to cooperate with those at the upper end of the standard 15. From the lower end of the body portion 45 depends a skirt portion 48 having dual functions, since the socket 49 provided by the skirt portion and lower face of the body portion 45 receives the upper end of the upper housing portion 12 in a loose fit (so that this upper end can rock in the socket 49) and the socket 40 also receives the upper end of an expansion coil spring 50 which bears against the lower face of the housing portion 45 while the lower end of the spring bears against the upper face of the shoulder or flange 24. The spring 50 surrounds the adjacent part of the standard 15 and resiliently spaces the socket structure 16 from the shoulder 24. Since the socket structure is secured to the support structure 13 the spring tends to force the housing 10 downwardly but reaches its limit of expansion before the lower end of the lower housing portion 11 contacts a supporting surface upon which the support struc-

ture 13 rests. It is now obvious that the entire housing may be rocked or tilted with respect to the support structure 13, and that if one grasps the housing 10, as at the upper portion 12, the weight of the support structure (either alone or with the added weight of the electric switch assembly 17 to be described and which is secured to the support structure) will cause the support structure to move toward the center of gravity, compressing the spring 50 until the upper edge of the upper housing portion 12 contacts the base of the socket 49. Not only will this prevent the housing 10 and support structure from separating further and the fixture may be carried about, but it also affects, in a desirable way, the switch assembly 17 to be next described. It is also obvious that, if the fixture is set down again, the housing 10 and support structure 13 will assume the relative positions shown in Figure 1 due to the expansion of the spring 50.

The electric switch assembly 17 in the example shown, comprises a fixed contact 55 provided for by a cylinder 56 of electricity-conducting metal carried by the standard 15 at, preferably just above the juncture of the standard and support portion 14 but electrically insulated therefrom, as by the collar 57 of dielectric material interposed between the cylinder 56 and standard 15 and a disc 58 of dielectric material between the lower end of the collar 57 and upper face of the support portion 14. The movable contact 59 is provided by a ring 60 of electricity-conducting material facing, but normally spaced from, the fixed contact cylinder 56 and supported by a suitable bracket 61 of dielectric material, preferably secured to the lower end of the upper housing portion 12 as by the rivets 22. When the parts of the fixture are as in Figure 1, the electric switch is open but when the housing 10 is tilted, as in Figure 2, the switch is closed, since the two contacts engage one another. The electric switch assembly does not take the place of a conventional switch of an electric lamp socket, since the novel lamp is adapted to be both lighted and extinguished with the parts coming to a position of rest as in Figure 1.

Associated with the switch assembly 17 is an electrically-operated on-and-off electric switch assembly 18, shown more particularly in Figure 3. This may comprise a solenoid 65, pawl 66 and ratchet wheel 67 associated therewith and electrical contacts 68 and 69, all carried in a suitable housing 70. The solenoid 65 comprises a conventional coil winding portion 71 and reciprocating armature 72. The latter is disposed to abut the intermediate portion of an inclined arm 73 pivotally carried, at its lower end, by the housing 70 and in turn, pivotally carrying the pawl 66 which is spring-urged by the retraction spring 74 to normally pivot toward the pivotal connection of arm and housing.

The free end of the pawl 66 is constructed and arranged to engage, one after another, the teeth 75 of the ratchet wheel 67, shown particularly in Figure 4, which wheel is pivotally carried by the housing 70 upon pivot 76. The wheel 67, in the example shown, has six teeth spaced substantially 60° apart, and is of a dielectric material. Secured to a face of the ratchet wheel 67 is an electric current-conducting member 77 provided, in the example shown, with three spaced-apart projections 78 substantially 120° apart which projections correspond in plan with the teeth 75 of the ratchet wheel. Each projection 78 has an arcuate edge 79 which merges

into a like arcuate edge of the associated tooth 15. Arranged for their free ends to rub over the arcuate edges mentioned, particularly the arcuate edges 19 are the two spaced apart electric contacts 68 and 69 of springy material. From Figures 3 and 4 it is apparent that the two contacts 68 and 69 will both either contact the member 77 at two edges 19 at the same time or, upon rotation of the ratchet wheel 60°, will rub upon only the dielectric material teeth at the same time. Consequently each 120° rotation of the ratchet wheel will first either open or close the switch just described and then either close or open the same. The contacts 68 and 69 may be carried by the housing 70 and electrically insulated therefrom.

With reference to the electric wiring 19, a lead 80 extends from one terminal of a conventional plug 81 to a block 82 and thence to one terminal in the base of the socket assembly 16. Electrically connected with the lead 86 is a lead 83 to the movable contact 59 of the switch assembly 17. From the other terminal of the plug 81 a lead 84 may extend to the block 82 and thence to the contact 68. Electrically connected with the lead 84 is a lead 85 to one end of the windings of the solenoid 65. From the other terminal in the socket assembly 16 a lead 86 may extend to the block 82 and thence to the contact 69. From the fixed contact 55 of the switch assembly 17, a lead 87 may extend to the block 82 and thence to the other end of the windings of the solenoid 65. If desired, a conventional thermostat 88 may be interposed in the wiring, such as in the lead 85, and suitably disposed within the housing 10.

From the foregoing, it is apparent that the fixture A, if a floor or desk lamp for example may be lighted or extinguished by simply tilting the housing 10 after which the housing is allowed to swing to a substantially vertical position. If the lower housing portion 11 and the base portion 14 are of metal, the protective covering 35 upon the vertical face of the flange 32 will deaden any sound when they meet. If the light is extinguished and it is desired to move the fixture to another location, the housing 10 is grasped and because the movable contact 59 will then move upwardly and out of facing relationship with the fixed contact 55, no matter if there is some oscillation, there will be no electric circuit closure. If one desires to move a lighted fixture A, one need but support the lower support portion 14 by one hand and steady the housing 10 with the other as the fixture is moved.

The thermostat 88 is desirable, since an object might be moved or tipped accordingly against the housing 10 and close the circuit to the solenoid, whereupon prolonged closure of the circuit might cause damage to the wiring, etc. By interposing the thermostat, the incidental warming up due to the solenoid circuit being closed will cause the thermostat to warm up and open the solenoid circuit, but when the thermostat again cools, it will close the circuit and energize the solenoid causing at 60° movement of the ratchet wheel and consequent changes in the lamp (from "off" to "on" or vice versa). A repetition of the thermostatic and solenoidal actions will take place with consequent flashing of the lamp, thus providing a visible signal so that the obstruction will be brought to notice and may be removed.

Various changes may be made to the form of

the invention herein shown and described without departing from the spirit of the invention or scope of the claims.

What is claimed is:

1. In an electric lighting fixture, a support structure including a standard, a housing structure, including a tubular portion spaced from and extending about said standard, means for supporting said housing structure by said support structure so that said tubular portion may be oscillated with respect to said standard structure, including a ring-shaped element fixedly secured to the inner face of said tubular portion, intermediate the ends of said tubular portion and normally spaced from said standard, and a second ring-shaped element fixedly secured to the outer periphery of said standard, the outer periphery of said second element being less in circumference than the interior circumference of said tubular portion and greater in circumference than the circumference of the outer periphery of said first element, said first element being disposed upon said second element, coupling means to attach an electric lamp to the upper end of said standard, including a socket structure having a body portion provided with a lower face and a downwardly opening skirt portion extending from said face, with the upper end of said tubular portion disposed within said skirt portion and normally spaced therefrom and from said face, resilient means within said skirt portion and upper end of said tubular portion normally urging said upper end away from said face, a pair of electric terminals carried by said coupling means, an electric contact secured to the inner face of said tubular portion below said first element, an electric contact secured to the outer face of said standard, normally spaced from said first contact and disposed within the path of travel of said first contact upon oscillation of said tubular portion, an off-and-on electric switch, electric means for actuating said switch upon abutment of said contacts, an electric lead from one of said contacts to one of said terminals, an electric lead from the other of said terminals to one of the terminals of said switch, a lead from the other of said contacts to the other terminal of said off-and-on electric switch, and means placing said electric means in circuit with said fixed contact and one of said terminals of said off-and-on switch.

2. In an electric lighting fixture, a support structure including a standard, a housing structure including a tubular portion spaced from and extending about said standard, means for supporting said housing structure by said support structure so that said tubular portion may be oscillated with respect to said standard structure, including a ring-shaped element fixedly secured to the inner face of said tubular portion, intermediate the ends of said tubular portion and normally spaced from said standard, and a second ring-shaped element fixedly secured to the outer periphery of said standard, the outer periphery of said second element being less in circumference than the interior circumference of said tubular portion and greater in circumference than the circumference of the outer periphery of said first element, said first element being disposed upon said second element, coupling means to attach an electric lamp to the upper end of said standard, including a socket structure having a body portion provided with a lower face and a downwardly opening skirt portion extending from said face, with the upper end of said tubular por-

tion disposed within said skirt portion and normally spaced therefrom and from said face, resilient means within said skirt portion and upper end of said tubular portion normally urging said upper end away from said face, a pair of electric terminals carried by said coupling means, an electric contact secured to the inner face of said tubular portion, an electric contact secured to the outer face of said standard below said first element and normally disposed within the path of travel of said first contact upon tipping of said tubular portion and disposed out of the path of travel of said first contact when said tubular portion contacts said face, an off-and-on electric switch, electric means for actuating said switch upon abutment of said contacts, an electric lead from one of said contacts to one of said terminals, an electric lead from the other of said terminals to one of the terminals of said switch, a lead from the other of said contacts to the other terminal of said off-and-on electric switch, and means placing said electric means in circuit with said fixed contact and one of said terminals of said off-and-on switch.

3. In an electric lighting fixture, a support structure including a standard, a housing structure including a tubular portion spaced from and extending about said standard, means for supporting said housing structure by said support structure so that said tubular portion may be oscillated with respect to said standard structure, including a ring-shaped element fixedly secured to the inner face of said tubular portion, intermediate the ends of said tubular portion and normally spaced from said standard, and a second ring-shaped element fixedly secured to the outer periphery of said standard, the outer periphery of said second element being less in circumference than the interior circumference of said tubular portion and greater in circumference than the circumference of the outer periphery of said first element, said first element being disposed upon said second element, coupling means to attach an electric lamp to the upper end of said standard, including a socket structure having a body portion provided with a lower face and a downwardly opening skirt portion extending from said face, with the upper end of said tubular portion disposed within said skirt portion and normally spaced therefrom and from said face, resilient means within said skirt portion and upper end of said tubular portion normally urging said upper end away from said face, a pair of electric terminals carried by said coupling means, an electric contact secured to the inner face of said tubular portion, an electric contact secured to the outer face of said standard below said first element and normally disposed within the path of travel of said first contact upon tipping of said tubular portion and disposed out of the path of travel of said first contact when said tubular portion contacts said face, and off-and-on electric switch, electric means for actuating said switch upon abutment of said contacts, an electric lead from one of said contacts to one of said terminals, an electric lead from the other of said terminals to one of the terminals of said switch, a lead from the other of said contacts to the other terminal of said off-and-on electric switch, and means placing said electric means in circuit with said fixed contact and one of said terminals of said off-and-on switch, said off-and-on switch and electrical means being carried by said support structure, and the weight of said support struc-

ture and last named means being greater than the weight of said housing structure.

4. In an electric lighting fixture, a support structure including a standard, a housing structure including a tubular portion spaced from and extending about said standard, means for supporting said housing structure by said support structure so that said tubular portion may be oscillated with respect to said standard structure, including a ring-shaped element fixedly secured to the inner face of said tubular portion, intermediate the ends of said tubular portion and normally spaced from said standard, and a second ring-shaped element fixedly secured to the outer periphery of said standard, the outer periphery of said second element being less in circumference than the interior circumference of said tubular portion and greater in circumference than the circumference of the outer periphery of said first element, said first element being disposed upon said second element, coupling means to attach an electric lamp to the upper end of said standard, including a socket structure having a body portion provided with a lower face and a downwardly opening skirt portion extending from said face, with the upper end of said tubular portion disposed within said skirt portion and normally spaced therefrom and from said face, resilient means within said skirt portion and upper end of said tubular portion normally urging said upper end away from said face, a pair of electric terminals carried by said coupling means, an electric contact secured to the inner face of said tubular portion, an electric contact secured to the outer face of said standard below said first element and normally disposed within the path of travel of said first contact upon tipping of said tubular portion and disposed out of the path of travel of said first contact when said tubular portion contacts said face, an off-and-on electric switch, electric means for actuating said switch upon abutment of said contacts, an electric lead from one of said contacts to one of said terminals, an electric lead from the other of said terminals to one of the terminals of said switch, a lead from the other of said contacts to the other terminal of said off-and-on electric switch, and means placing said electric means in circuit with said fixed contact and one of said terminals of said off-and-on switch, the weight of said support structure being greater than the weight of said housing structure.

5. In an electric lighting fixture, a support structure including a hollow base, providing a chamber, and a standard; a housing structure, including a lower hollow portion having an open lower end, and a tubular portion extending upwardly from the lower hollow portion, said lower hollow portion being disposed about the upper part of said base and spaced therefrom, and the tubular portion being disposed about the lower part of said standard and spaced therefrom; means for supporting said housing structure from said support structure so that said housing structure may be rocked from side to side; means to couple an electric lamp to the upper end of said standard; a pair of electric terminals carried by said last-named means; electric switch means carried within said housing structure and by said support structure and operable upon rocking of said housing structure; an off-and-on electric switch, electric means for actuating said last-named switch upon closing said first-named switch and disposed within said chamber; an

electric lead from one of the contacts of said first-named switch to one of said terminals; an electric lead from the other of said terminals to a contact of said last-named switch; a lead from the other contact of said first-named switch to the other contact of said second-named switch; a thermostat interposed in one of said leads, and disposed within said chamber adjacent said electric means; and means placing said electric means in circuit with said fixed contact and one 10 of said contacts of said off-and-on switch.
